UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

WEB MOISTENING DEVICE

Application filed June 4, 1926, Serial No. 113,592. Renewed November 17, 1930.

This invention relates to the feeding of the web in a printing press from the press to the folder. It is customary to dampen the edges of the web before they go through the press so that these edges will be slightly expanded by the water and flattened out between the several pairs of rows through which they pass. In cases in which the web is slit after it is passed through the press this leaves slit webs with one edge dampened and the other dry. This obviously is a bad situation as it is likely to skew the web as it passes over the turning bars and even through pairs of guiding rolls.

The principal object of this invention is to provide for overcoming this difficulty so that both edges of each slit web after it is slit will be dampened.

Reference is to be had to the accompanying drawings in which

Fig. 1 is a side view of a printing press, diagrammatic in form, showing the application of this invention thereto;

Fig. 2 is a diagrammatic plan with the web broken away to show the means for dampening it;

Fig. 3 is a side view showing the application of another dampening means;

Fig. 4 is a plan similar to Fig. 1 of the modification shown in Fig. 3;

Fig. 5 is a side view of another modification; and

Fig. 6 is a plan of the same.

For the purpose of securing a dampened region along the web at the center or at any other point at which it is to be slit, I simply provide a water fountain 10 extending all the way across the press near the web roll 11 and place a shaft 12 across the fountain.

In addition to having two rolls 13 for the fountain applying moisture to the edges of the web along the regions 14 thereof, I employ also a central roll 15 for applying moisture along the region 16 at the center of the web or other position in which the web is to be slit. This roller is practically twice the width of the rollers 13.

The web then travels from the rollers 13 and 15 through the printing couple and to the slitter 18. This slitter cuts the web along

the center of the dampened area 16, separating it into two webs as will appear. Now both of these webs are dampened at both edges so that the two edges will pass over turner bars 20 and act alike. There is no tendency to draw either web to one side on account of any difference in the edges. One web is taken through the turner bars 20 in the usual way and brought under the other web to the folder 21.

In the form shown in Figs. 3 and 4, the conditions are substantially the same except that the moistening is done by two steam jets 23 at the sides and a steam jet 24 at the center which provides similar conditions on the web of paper.

In the form shown in Figs. 5 and 6, the rollers 13, although not shown in these figures, are used in a similar manner to that shown in Figs. 1 and 2 but it will be understood that these rollers 13 are mounted in the usual way and without any central roller. In this case an extra fountain 25 is employed located beyond the slitter 18. There is no need of any moistening before the slitting takes place and furthermore the moistening of the paper adds difficulty in some cases to the slitting of the web along the moistened portion. In this fountain is a roll 26 which applies a strip of moisture to the web in line with the slitter 18 so that immediately after slitting the two webs are moistened on both edges.

With any of these constructions the slit webs, as they pass from the slitters, no matter how many in number they may be, are moistened along both edges. The two edges of each portion of the web will act alike throughout the rest of the manipulation of the webs.

Although I have illustrated and described only three forms of the invention I am aware of the fact that other modifications can be made therein by any person skilled in the art and that the invention can be applied in other ways without departing from the scope of the invention as expressed in the claims. Therefore I do not wish to be limited to any one of these forms herein disclosed, but what I do claim is:

1. In a printing press, the combination with

- means for feeding the web through the printing couple to the folder and means for slitting the web, of moistening devices for moistening that portion only of the web which comprises the two outer edges thereof and means for moistening that portion of the web which comprises each side of the slit so that the two edges bordering the slit will be moistened.
2. The combination with a printing press having a printing couple and a slitter, of a moistening device for moistening the two outside edges only of the web and means for moistening the web along a line which includes the edge on each side of the slit which is made by the slitter.
3. In a printing press, the combination with means for feeding the web and means for slitting the web, of moistening devices for moistening only the two outer edges of the web, and means for moistening the web at a point in alignment with the slitting means and leaving unmoistened that portion of the web which lies between the margins thereof.
4. In a printing press, the combination with means for printing pages upon a web of paper, the said web having a central longitudinal area which is to be slit, of means for moistening the said area and means for moistening the margins of the web so that after the web is slit all four edges of the slit web will be moistened, while the remainder of the web remains unmoistened.
5. In a printing press the combination with means for feeding a web and means for applying moisture to that portion only along the outer edges of the web, of means for applying a narrow strip of moisture along the web in a line between its edges, an unmoistened portion of the web remaining between the outer moistened edges and the intermediate moistened strip.
6. In a printing machine, the combination of means for feeding a web with a central slitting device for slitting the web half-way between its edges and a moistening device for moistening only the extreme outer edges of the web, of means for continuously moistening a strip on the web at the center, leaving an unmoistened portion between the moistened outer edges and the center moistened strip.
7. The combination with a printing press having a printing couple, and a slitter, of steam jets for moistening only the two outer edges of the web and a steam jet for moistening the web at a point between the two edges and in alignment with the slitter, leaving an unmoistened portion between the moistened outer edges and the two inner moistened edges.
8. The combination in a printing machine, of a web roll, printing couples, and a slitter, of means adjacent to the web roll for moistening the margins of the web and means in longitudinal registration with the slitter for

moistening a narrow longitudinal area at the point where it is to be slit.

In testimony whereof I have hereunto affixed my signature.
